UNITED STATES PATENT OFFICE.

ROBERT RICHARDSON, OF GLASGOW, SCOTLAND, ASSIGNOR TO JOHN HASTIE AND COMPANY, LIMITED, OF GREENOCK, SCOTLAND.

CONTROLLING-VALVE FOR STEERING-ENGINES.

SPECIFICATION forming part of Letters Patent No. 761,253, dated May 31, 1904.

Application filed January 15, 1903. Serial No. 139,143. (No model.)

To all whom it may concern:

Be it known that I, ROBERT RICHARDSON, a subject of the King of the United Kingdom of Great Britain and Ireland, residing at 16 Jamieson street, Govanhill, Glasgow, Scotland, have invented certain new and useful Controlling-Valves for Steering-Engines, (for which applications for patents have been made in Great Britain, No. 16,525, dated July 24, 1902, and 10 in Germany, dated December 20, 1902,) of which the following is a specification.

This invention relates to steam steering-engines in which the direction and extent of motion are regulated by a controlling-valve which 15 is automatically brought back after each action into its middle or neutral position. The controlling-valve in such engines is usually for ease in handling a piston-valve which besides being difficult to keep steam-tight cannot 20 effectually close the passages to the distributing-valves of the steering-engines owing to the engines ceasing to operate, and therefore ceasing to actuate the controlling-valve when these passages are so nearly closed as 25 to supply insufficient steam, and consequently large leakage of steam occurs. For the purpose of overcoming this difficulty a stop-valve operated by the controlling-valve has been introduced to cut off the steam-supply when the 30 controlling-valve is in the neutral position; but it is also apt to remain partially open.

The object of this invention is to insure that the valve provided for cutting off the steam-supply to the controlling-valve of steam steering-engines shall be open and kept open when the controlling-valve is moved in either direction, but shall be effectually closed to prevent leakage of steam when the neutral position of the controlling-valve is reached. For that 35 purpose the cut-off valve is so constructed and arranged that it is opened by the steam-pressure on exhausting the steam which acts on its opposite face to normally close it, such exhaust being effected by the action of the controlling-valve on an exhaust valve or valves.

The invention is illustrated by way of ex-

ample in the accompanying drawings, in which—

Figure 1 is a longitudinal section of the controlling-valve casing of a steering-engine, 50 showing a modification in which a single vertically-moving cut-off valve is employed and operated by exhaust-valves situated at each end of the controlling-valve; and Fig. 2 is a like view showing a modification in which a 55 cut-off valve moving horizontally is placed at either end of the controlling-valve casing. Fig. 3 shows in vertical section a modified construction of the cut-off valve and relative parts. Fig. 4 is a longitudinal vertical section of a steam steering-engine, showing the application thereto of the construction illustrated in Fig. 3.

In the example represented at Fig. 1 the cutting-off valve *a* is formed on or attached to 65 a piston *a'*, fitted in a small cylindrical casing *b*, the inner end of which forms the seat *c* for the valve *a*. The outer end of the cylinder is connected by passages *d* to a small valve-casing *e* at each end of the controlling-valve casing *f*, these end casings *e* communicating each through a valve-orifice *g* with the corresponding end of the controlling-valve casing. In these valve-orifices are seated small valves *h*, which are normally closed by springs *i*, but 75 one or other of which is pressed open by the controlling-valve *j* when it is moved slightly from the central position. The opening of either of these small valves *h* allows the steam which has leaked past the piston *a'* on the cutting-off valve *a* to escape by way of the passage *d* from the outer end of the cylinder *b* into and through the exhaust-chamber *k* of the controlling-valve, (which in this instance is at either end of the valve *j*,) or to otherwise 80 exhaust, whereupon the pressure of the steam which is admitted at *b'*, acting on the inner side of the piston *a'*, forces it outward and raises the cutting-off valve *a* from its seat, whereupon steam is admitted to and through 85 the controlling-valve *j* to the ports *l*, leading 90 to the steering-engine. Immediately on the

controlling-valve *j* returning to its mid-position the small valve *h* in the end of the casting *e* is closed by the spring *i* or by the pressure on its back, and exhaust of steam being

5 prevented the steam-pressure, acting on the outer side of the piston *a'*, effectually closes down the valve *a*, which cuts off steam to the controlling-valve, this action being assisted by a spring or by gravity when, as is usual, 10 the valve closes downward.

The movements of the controlling-valve *j* to right and left is effected in the usual way, as by the lever-arm *m* on the shaft *n*.

In the modification represented at Fig. 2 a 15 cut-off valve *a* is fitted at each end of the controlling-valve casing *f* in a valve-orifice *e'*, through which the boiler-steam from the inlet *b'* is admitted to the ends of the controlling-valve pistons *j* instead of, as is usual, to the 20 space between them, which latter in the present instance is connected to the exhaust-port *o*. Each cut-off valve *a* is formed with a piston *a'*, fitting in a short cylinder *b* at the end of the valve-casing *f*, the cylinder *b* being 25 formed with a dividing-web *b'*, in which is fitted a small auxiliary valve *h*, closed by a spring *i*, and whose stem *h'* passes through the cut-off valve *a* and projects into the controlling-valve casing. On the movement of 30 the controlling-valve *j* in either direction from its neutral position a tap *j'* on its end strikes the stem *h'* of the auxiliary valve *h* at that end and opening it allows the steam at the back of the cut-off valve *a* to escape to 35 exhaust by the passage *k'*, whereupon the valve *a* opens and steam is admitted to the controlling-valve casing *f*, whose ends communicate by means of a passage *f'*. On the controlling-valve returning to the neutral position 40 the auxiliary valve *h* first closes and the steam-pressure passing to the back of the cut-off valve *a* closes it also, a spring *p* being used to facilitate the closing operation.

In the modification represented at Figs. 3 45 and 4 the cut-off valve *a* is normally held on its seat apart from the steam-pressure acting on it by means of a spring *l* and link or rod *m*, extending through an orifice in the valve and engaged by a nut *m'*, and through this 50 rod is carried a tappet or pin *n*, which is acted on by a cam *o* on the controlling-valve stem *o'* to raise the auxiliary valve *h* from its seat against the power of a spring *h'* and permit of the exhaust of steam from the back of the 55 valve *a* when the controlling-valve spindle *o'* is turned. The exhaust of the steam at the back of the valve *a* permits of the steam admitted at *b'* acting on the inner side of the valve *a* and lifting it from its seat to admit 60 steam to the controlling-valve through the casing *p*, and on the controlling-valve spindle *o'* returning to its neutral or mid-position the tappet *n* drops and the auxiliary valve *h* is

closed by the spring *h'*, whereupon the steam leaking past the valve *a* and acting on the 65 greater area of its upper side closes it, this action being aided by the spring *l*.

In Fig. 4 a steering-engine is shown as fitted with the controlling-valve described with reference to Fig. 3. The engine itself is of 70 an ordinary type having a crank-shaft *Q*, on which is a worm *Q'*, meshing with a worm-wheel *R* on a shaft *R'*, which carries the usual chain-barrel *R''*, from which the ship's rudder is actuated. The worm *Q'* also meshes with 75 a worm-wheel *S*, fast on a sleeve *S'*, on which is formed the bevel *s*, meshing with the usual differential gear *O³* *O⁴* and through which sleeve the handing-shaft *O⁶* passes.

In the operation of the engine the handing-shaft *O²* is turned by the steersman to turn the shaft *O⁶*, or said shaft may be turned by means of bevel-gear *O⁷* from the ship's bridge. The bevel *O⁴*, fast on the shaft *O⁶*, imparts a turning movement to the bevel *O³*, which, owing to its engagement with the then stationary bevel *s*, is swung around the shaft *O⁶* and carries with it the segment *O⁵*, with which it is integral, and thereby the segment *O⁸* and with it the controlling-valve spindle *O'* is 90 turned to open the steam-ports to the steering-engine. On the operation of the engine the worm *Q'*, acting on the worm-wheel *S* and bevel *s*, brings back the differential bevels and segments thereby operated and returns 95 the controlling-valve spindle *O'* to the initial position of rest. On the first movement of the controlling-valve spindle *O'* the cam *O* on its end acting on the exhaust-valve *h* allows to escape to exhaust the steam acting to close 100 the stop-valve *a*, and said valve would then rise to admit boiler-steam to the controlling-valve casing. On the return movement of the control-valve spindle the cam *O* allows the exhaust-valve *h* to close, and then the steam-pressure on both sides of the valve *a* being equalized the valve *a* closes on its seat by 105 gravitation, the steam-pressure on its upper side thereafter maintaining it tightly closed. The piston *a'*, to which the stop-valve *a* is attached, is a loose fit in its casing, that boiler-steam leaks past the piston and no passages are made in the latter.

Having now described the invention, what I claim, and desire to secure by Letters Patent, is—

1. In a controlling-valve for steering-engines, the combination of a cut-off valve adapted to cut off the steam from the boiler to the casing of the controlling-valve, means whereby said cut-off valve is opened when the controlling-valve is moved from its neutral position by the exhaust of steam which normally holds said cut-off valve in closed position, substantially as described.

2. In a controlling-valve for steering-en-

gines the combination with a cutting-off or stop valve provided to close off the boiler-steam of a piston thereon working in a cylinder having connections to an exhaust valve or 5 valves operated as described by the movement of the controlling-valve from the neutral position.

In witness whereof I have hereunto set my hand in presence of two witnesses.

ROBERT RICHARDSON.
